No. 37,072.

Patented August 9, 1904.

UNITED STATES PATENT OFFICE.

WILL H. BRADLEY, OF CONCORD, MASSACHUSETTS, AND MORRIS F. BENTON, OF NEW YORK, N. Y., ASSIGNEES TO AMERICAN TYPE FOUNDERS' COMPANY, OF JERSEY CITY, NEW JERSEY, A CORPORATION OF NEW JERSEY.

DESIGN FOR A FONT OF TYPE ORNAMENTS.

SPECIFICATION forming part of Design No. 37,072, dated August 9, 1904.

Application filed July 5, 1904. Serial No. 215,412. Term of patent 14 years.

To all whom it may concern:

Be it known that we, WILL H. BRADLEY, a resident of Concord, in the county of Middlesex and State of Massachusetts, and MORRIS F. BENTON, a resident of New York, in the county and State of New York, citizens of the United States, have invented a new, original, and ornamental Design for a Font of Type Ornaments, of which the following is a specification.

This design is shown in the accompanying drawings, in which it will be seen that the font comprises eight ornamental characters.

What we claim is—

The ornamental design for a font of type 15 ornaments as herein shown.

WILL H. BRADLEY.

MORRIS F. BENTON.
